UNITED STATES PATENT OFFICE.

LEROY S. PFOOTS, OF CANTON, OHIO, ASSIGNOR, BY MESNE ASSIGNMENTS, TO THE MILLER PASTEURIZING MACHINE COMPANY, OF CANTON, OHIO, A CORPORATION OF OHIO.

LIQUID-TREATING APPARATUS.

1,352,215.

Specification of Letters Patent. Patented Sept. 7, 1920.

Application filed June 16, 1916. Serial No. 104,128.

To all whom it may concern:

Be it known that I, LEROY S. PFOOTS, a citizen of the United States, residing at Canton, in the county of Stark and State 5 of Ohio, have invented certain new and useful Improvements in and Relating to Liquid-Treating Apparatus, of which the following is a specification.

This invention relates to apparatus for 10 heating and cooling liquids, such as milk, more particularly to liquid treating apparatus of the surface tubular type over which the liquid flows by gravity.

One object of the invention is to control 15 and guide the liquid material to the circulating means for the heating or cooling medium.

Another object of the invention is to control 20 the delivery of the liquid to the circulating means for the heating or cooling medium to avoid waste of the liquid and unsanitary conditions.

Another object of the invention is to provide 25 an improved construction of medium circulating means adapted to economically heat or cool the liquid.

Other objects of the invention will be apparent to those skilled in the art to which my invention relates from the following description taken in connection with the accompanying drawings.

For the purpose of illustration I have, in the accompanying drawings, shown and herein described one form of apparatus embodying my invention.

Figure 1 is a perspective view of a heating and cooling apparatus embodying my invention.

Fig. 2 is a transverse sectional view, the 40 medium circulating means being shown in end elevation.

Fig. 3 is a longitudinal sectional view, the medium circulating means being shown in side elevation.

Fig. 4 is a fragmentary transverse sectional view, somewhat enlarged, of the apparatus.

Fig. 5 is a fragmentary longitudinal sectional view, somewhat enlarged, parts of 50 the apparatus being shown in elevation.

Fig. 6 is a fragmentary transverse sectional view of the liquid holder and distributor.

Fig. 7 is a bottom plan view of the parts 55 shown in Fig. 6.

Fig. 8 is a fragmentary sectional view on the line 8—8 of Fig. 6.

Fig. 9 is a detail view.

Fig. 10 is a fragmentary sectional view of the lower end of a supporting bar. 60

In the drawings, 1 indicates as an entirety a frame work, preferably comprising a pair of spaced members 1^a, 1^a. Each member 1^a may be formed from bars or piping 1^b, suitably connected together by braces 1^c, 1^c. 65 The opposite end of the braces are secured to the bars 1^b in any well known manner, as by bolts 1^d. The bars 1^b preferably diverge from each other at their lower ends. The lower ends of the bars may be provided 70 with caps 1^e. The caps 1^e may be adjustably secured to the bars 1^b.

2 indicates as an entirety the circulating means for a heating or cooling medium. The circulating means 2 is preferably arranged in sections or units, each indicated at 2'. In the illustrated construction, I

provide two sections 2', one above the other, so that their pipes or conduits will be in the same vertical plane. Each unit 2' comprises a series of pipes 2^a connected at their opposite ends to manifolds 2^b, 2^b', in any well known manner. 2^a' is a member extending through each pipe 2^a, and substantially from end to end thereof. Each member 2^a' may 80 be formed from a hollow section of material and be provided with projecting lugs 2^c to maintain the member 2^a' substantially concentric to the pipe 2^a, to form a relatively small or thin medium circulating space entirely around the member 2^a'. The lugs 2^c are preferably formed integral with and uniformly spaced around a ring 2^c', which fits the pipes 2^a'. Any desired number of rings 2^c' may be placed on and spaced along 85 each pipe 2^a' to maintain it at all points concentric to the adjacent pipe 2^a.

2^d indicates suitable plugs or closing devices fitted in a liquid tight manner to the opposite ends of each pipe 2^a' and serving to keep the heating or cooling medium from entering the pipe 2^a' and filling it.

2^e indicates a device secured in any well known manner to and extending from each plug 2^d. The outer end of each device engages the front wall of the adjacent manifold and serves to space the end of the adjacent pipe 2^a' therefrom, and in coöperation with the spacer 2^e at the opposite end of the adjacent pipe 2^a' to prevent move- 105 110

ment endwise or longitudinally of the adjacent pipe 2^a. The inner ends of the spacers 2^e are preferably connected by screw threads with the plugs 2^d, whereby 5 they can be adjusted to properly position the pipes 2^a. By making the pipes 2^a of proper length and providing the spacing devices 2^e, the pipes are prevented from extending into the manifolds and obstruct- 10 ing the flow of the medium therethrough. The manifolds 2^b, 2^{b'}, are preferably provided with openings which permit access thereinto, to the pipes 2^a, to the interior of the pipes 2^a, and to the spacers 2^e. The 15 openings are preferably closed by suitable caps 2^f, which may have screw threaded engagement with the walls of the openings. By the form of construction, above described, it will be seen that a relatively 20 small quantity of fluid is required to fill the circulating space throughout the entire system. It will be readily understood that under such circumstances the apparatus can be run economically with efficient re- 25 sults. 2^h, 2ⁱ, indicate the inlet and outlet connections for the heating or cooling medium connected, respectively, to the lower and upper ends of one of the manifolds of each unit, such as the manifold 2^{b'}. 30 2^k indicates a projection, such as a pipe, extending from the upper end of each manifold 2^b substantially in line with the adjacent outlet connection 2ⁱ. The projection 2^k and adjacent outlet 2ⁱ fit into sockets 35 formed in the adjacent braces 1^c and thereby serve to connect the adjacent section or unit 2' to the supporting members 1^a. The sections or units may be connected to the members 1^a in any desired manner. 40 3 indicates a holder for the liquid. The holder 3 is arranged above and extends longitudinally substantially from end to end of the medium circulating means 2. The holder 3 is provided with one or more series 45 of openings 3' through which the liquid flows onto the pipes 2^a of the medium circulating means 2. The holder 3 may be supported in position by any suitable means, that shown for illustrative purposes 50 comprising a pair of yokes 3^a, each having a seat 3^b resting on the upper end of the adjacent manifold 2^b or 2^{b'}, a rectangular frame 3^c connected in any desired manner to the opposite ends of the yokes 3^a; and 55 a plate 3^d having depending flanges 3^e which fit over the rectangular frame 3^c. The plate 3^d is formed with an opening 3^{d'} to receive the holder 3. The walls of the opening 3^{d'} engage with flanges or turned 60 over edges 3^x of the holder 3 to removably support the latter in operative position. 3^e indicates a cover for the holder 3. 4 indicates a flow wall or liquid guide for the liquid flowing through the opening 65 or openings 3' in the holder 3. The pur-

pose of this wall or guide is to control the stream or streams of liquid flowing from the opening or openings 3' and direct it or them downwardly to and against the uppermost pipe 2^a. In apparatus of this character considerable difficulty has heretofore been experienced in boring or forming the hole or holes through the holder so that the stream or streams would flow in a downward direction onto the circulating pipes. 70 In forming the holes, the forming tool usually leaves the metal around the edge of each opening more or less rough or with minute projections or pieces of material, which divert or tend to divert the streams 75 in various directions; causing some of the streams to flow toward each other, thus effecting an uneven distribution of the liquid over the pipes 2^a, and other streams to flow laterally away from the pipes 2^a onto the 80 inclosing casing or flooring, thus resulting in waste of material and unsanitary conditions. My flow wall or guide causes the stream or streams to flow directly downwardly onto the pipes and thus entirely overcome these 85 objections. This result is accomplished by extending the wall downwardly from the discharge port or end of the opening 3' preferably parallel to the axis thereof and disposing it in alignment with or a plane 90 which is tangential to one wall of the opening 3'. Where, as in the apparatus herein disclosed, a plurality of discharge openings 3' are arranged in a row, a continuous flow wall 4 may be provided for the sake 95 of simplicity and ease of manufacture. Where two rows of openings 3' are provided, as shown in the drawings, they are 100 preferably disposed equal distances to either side of a line passing through the axes of the pipes 2^a and a bar 4' having a width equal to the distance between the inner side walls of the openings 3' is arranged between them so that the opposite side walls of the bar will serve to guide the streams of liquid 110 from both rows of openings downwardly. When two rows of openings are provided, the openings 3' in one row may be staggered relative to the openings 3' in the other row 115 to insure substantially uniform distribution of the liquid over the medium circulating means 2. 120 In the preferred form of construction, I form the flow wall or walls 4 integral with the walls through which the discharge openings extend to insure the disposition of each wall 4 in a plane tangentially to the side walls of the adjacent openings 3'. For this purpose, I provide on the bottom of the holder 3 a T-bar 4^b in the arms of which are formed discharge openings 3^{a'} registering with the openings 3' in the holder 3. 125 As shown, the leg of the T is of a width equal to the distance between the inner side walls of the openings 3^{a'} so that the oppo- 130

site side faces of the leg will be disposed in a plane which extends tangential to the inner walls of the openings 3^a.

The liquid to be treated is delivered to 5 the holder 3 in any suitable manner. From the holder 3, the liquid flows by gravity over the pipes 2^a successively from the upper to the lower one, from which it drops into a receiver 5. The receiver is provided 10 with a suitable discharge pipe 5' to convey away the liquid. The receiver 5 is preferably supported at its opposite ends by arms 5^a extending inwardly from the braces 1^c.

6 indicates a sectional casing of any 15 desired form for inclosing the apparatus. The casing 6 preferably comprises a skeleton frame work 6' and a plurality of swingable sections 6^a which are pivoted and detachably secured to the frame work of the casing in 20 any well known manner. The upper and lower ends of the casing 6 are preferably constructed and arranged to coöperate with the flanges 3^e and the side walls of the receiver 5 to entirely inclose the pipes 2^a. 25 The swingable sections are preferably held in position by pivoted latches 6^b.

As one application of my invention I have shown it correlated with a circulating means or system through which either a 30 heating medium or a cooling medium may be caused to flow to heat or cool milk. The milk is conveyed by suitable piping or other means to the holder 3 from which it flows through the openings 3', 3^a', downwardly 35 onto the uppermost pipe 2^a, the flow walls 4 causing the streams emerging from the lower ends of the openings 3^a' to flow straight or downwardly independently into engagement with the adjacent pipe 2^a from 40 which it flows to each of the other pipes 2^a successively, finally dropping into the receiver 5. While flowing over from one pipe 2^a to another, the temperature of the milk is raised or lowered according to the temperature 45 of the medium flowing through the pipes.

By causing a quantity of milk to pass over the pipes and causing a heating medium to pass therethrough, the apparatus 50 may first serve to heat or pasteurize the milk to any desired temperature; then by causing the same body of milk to flow over the pipes and causing a cooling medium to flow therethrough, the milk may be cooled 55 to any desired degree. It will thus be seen that the apparatus may be used either as a heater or cooler, or first as a heater and then as a cooler, or vice versa, as circumstances may require.

60 To those skilled in the art of making apparatus of the class described, many alterations in construction and widely differing embodiments and applications of my invention will suggest themselves, without departing 65 from the spirit and scope thereof.

My disclosures and the description herein are purely illustrative, and are not intended to be in any sense limiting.

By the use of my invention I am enabled to direct the streams of liquid downwardly 70 substantially vertically and independently of each other. The effect of this operation is to avoid waste of the liquid on the one hand and on the other hand, substantially uniform distribution of the liquid over the 75 pipes 2^a, whereby the apparatus may operate efficiently in the transfer of the heat either to or from the liquid flowing over the pipes.

What I claim is:

1. A liquid distributor comprising a 80 holder formed with a discharge opening and a wall depending from the discharge port of said opening in a plane parallel to its axis and constituting a continuation of one side wall of said opening for directing or 85 guiding the stream discharged therefrom.

2. A liquid distributor comprising a 90 holder formed with a discharge opening in its bottom and a flow wall arranged in alinement with and extending from one side wall 95 of the discharge opening for directing a stream discharged from said opening against a surface, said flow wall extending throughout its length in a direction parallel to the axis of said discharge opening.

3. A liquid distributor formed with a discharge opening and a flow wall extending from the discharge opening in the direction of its axis and disposed in alinement with the side wall of the opening, in combination 100 with a temperature changing medium circulating pipe arranged in position to have the liquid from the opening discharged thereagainst.

4. A liquid distributor formed with a series 105 of discharge openings in its bottom adapted to direct streams of liquid downwardly, and a flow wall common to and extending from the discharge openings in the direction of their axes and disposed in alinement with the side walls of the openings.

5. A liquid distributor formed with a series 115 of discharge openings in its bottom adapted to direct streams of liquid downwardly, and a flow wall common to and extending from the discharge openings in the direction of their axes and disposed in alinement with the side walls of the openings, in combination with a medium circulating pipe arranged in position to have the liquid from 120 the opening discharged thereagainst.

6. A liquid distributor formed with a plurality of rows of discharge openings in its bottom adapted to direct streams of liquid downwardly, and a flow wall arranged between the rows of openings extending from the discharge ports thereof in the direction of their axes, said wall being of a width equal to the distance between the inner walls 125 of the openings whereby its opposite faces 130

are disposed in alinement with the inner walls of the openings.

7. A liquid distributor formed with a plurality of rows of discharge openings in its bottom adapted to direct streams of liquid downwardly, the openings of one row being staggered relative to the openings of the other row, and a flow wall arranged between the rows of openings extending from the discharge ports thereof in the direction of their axes, said wall being of a width equal to the distance between the inner walls of the openings whereby its opposite faces are disposed in alinement with the inner walls of the openings.

8. The combination with a series of horizontal pipes arranged in a vertical plane and adapted to form a conduit or conduits for a heating or cooling medium, of a liquid

holder arranged above the pipes, said holder being formed with a series of discharge openings in its bottom adapted to direct streams of liquid downwardly, and a flow wall extending from the discharge openings in the direction of their axes and disposed in alinement with the side walls of the openings.

9. The combination of a liquid holder formed with two rows of discharge openings in its bottom, and a T member connected to the bottom of said holder, the arms of said member being formed with openings registering with the openings in the bottom of said holder and the leg of said member being of a width equal to the distance between the inner side walls of the rows of openings.

10. In apparatus of the character described, the combination of a pair of manifolds formed with alined openings in their opposing walls, a pipe fitting into each pair of alined openings at its opposite ends, a closed cylindrical member removably mounted within and concentrically of each pipe and extending from end to end thereof, and means for preventing endwise movement of each closed cylindrical member relative to the adjacent pipe.

11. In apparatus of the character described, the combination of a series of medium circulating pipes, manifolds to which the opposite ends of said pipes are connected, a member arranged concentrically within each of said pipes and over which the medium flows, the opposite outer walls of said manifolds being formed with openings, the axes of which are in line with the axes of said pipes, removable caps for closing said openings, and adjustable spacing devices between the opposite ends of said members and the caps for the openings in said manifolds.

12. In apparatus of the character described, the combination of a pair of mani-

folds, a series of medium circulating pipes connected at their opposite ends thereto, a member concentrically arranged in each pipe and over which the medium flows and extending substantially from end to end thereof, and spacing members between the opposite ends of said member and the opposite outer walls of said manifolds.

13. In apparatus of the character described, the combination of a series of medium circulating pipes, manifolds to which the opposite ends of said pipes are connected, a member arranged concentrically within each of said pipes and over which the medium flows, the opposite outer walls of said manifolds being formed with openings, the axes of which are in line with the axes of said pipes, and removable caps for closing said openings.

14. In a liquid treating apparatus, the combination with a hollow member for a temperature controlling medium, of a liquid holder above and extending longitudinally of said member, and formed with two rows of openings for discharging liquid from said holder upon the surface of said member, said rows of openings being disposed at opposite sides of and equal distance from a vertical plane cutting the axis of said member, and flow walls each in vertical alinement with one side wall of each opening.

15. In a liquid treating apparatus, the combination with a hollow member through which circulates a temperature controlling medium, of a liquid holder above and extending longitudinally of said member and formed with two rows of openings for discharging liquid from said holder upon the surface of said member, and a vertical flow wall common to each said row of openings and depending from said holder in a plane parallel to the axis of said openings for controlling the liquid as it flows therefrom onto said member.

16. In a liquid treating apparatus, the combination with a hollow member through which circulates a temperature controlling medium, of a liquid holder above and extending longitudinally of said member and formed with two rows of openings for discharging liquid from said holder upon the surface of said member, and vertical flow walls arranged between said openings and common thereto, respectively, and extending downwardly from said holder in planes parallel to the axes of said openings for controlling the liquid as it flows therefrom onto said member.

In testimony whereof I affix my signature in the presence of two witnesses.
